UNITED STATES PATENT OFFICE.

JAMES G. MACLAREN, OF SYRACUSE, NEW YORK, ASSIGNOR, BY MESNE ASSIGNMENTS, TO THE LAMSON COMPANY, A CORPORATION OF MASSACHUSETTS.

RECEIVING TERMINAL FOR PNEUMATIC-DISPATCH TUBES.

Application filed December 30, 1921. Serial No. 526,010.

To all whom it may concern:

Be it known that I, JAMES G. MACLAREN, a citizen of the United States, and resident of Syracuse, in the county of Onondaga and State of New York, have invented certain new and useful Improvements in Receiving Terminals for Pneumatic-Dispatch Tubes, of which the following is a specification.

The present invention relates to a dispatch apparatus, and more particularly, to an apparatus for receiving and disposing of the carriers in a pneumatic-dispatch apparatus. More particularly it relates to an apparatus by which carriers may be received by an operator or may be passed to a reserve operator. The various features of the invention are illustrated in the accompanying drawings in Fig. 1 illustrates a side elevation of an apparatus for receiving and disposing of the carriers in a pneumatic-dispatch apparatus. More particularly it relates to an apparatus by which carriers may be received by an operator or may be passed to a reserve operator.

This application is a continuation in part of the view of Fig. 1 of a guard or retainer of my prior application Serial No. 376,976, filed April 27, 1920.

In the operation of pneumatic-dispatch apparatus, it is customary to discharge carriers containing money or other articles from certain sources to a single operator, the work being so arranged that each operator will receive only a definite number of carriers which is within the operator's capacity to handle and dispose of. At certain periods, it sometimes happens that carriers are received at a rate considerably above the normal and above that by which they can be conveniently handled or taken care of. When this occurs for a considerable period of time, the surplus or overflow of carriers received above the normal rate, must be transferred to a reserve operator, if delays and confusion are to be avoided.

An object of the present invention is to provide a pneumatic-dispatch apparatus in which carriers may be received in position convenient to an operator or may at the will of the operator be deflected to a reserve operator.

Another object of the invention is to provide a receiver for pneumatic-dispatch apparatus in which carriers may be received by an operator or at will deflected to a reserve operator or in which carriers may be received and an excess or overflow of carriers may be automatically deflected to a reserve operator.

Another object of the invention is to provide a simple and inexpensive receiver for a pneumatic-dispatch apparatus by which carriers may be received at the normal rate and

Fig. 2 is a detailed view at right angles to Fig. 1 illustrating a guard or retainer embodying the preferred form of the invention, and

Fig. 2 is a detailed view at right angles to Fig. 1 illustrating a guard or retainer embodying the preferred form of the invention, and

In the present invention, the carriers discharged from the end of the discharge tube at a normal rate are received and retained in an inclined position in the lower part of a vertically positioned tubelike receiver, the front part of the receiver being cut away sufficiently to permit the carrier to be easily grasped and removed. When carriers are discharged at a rate above the normal, the overflow of carriers are deflected through a second opening or passageway positioned in the receiver somewhat above the lower opening through which the receivers are normally removed by the operator. When, for any reason, no carriers are to be deflected or passed to the reserve operator regardless of the rate discharged, the passage of carriers through the upper opening is positively prevented by means of a guard or retaining member which is movable over the opening in a position to prevent the passage of carriers therethrough. At times it is desirable to have all of the carriers discharged to the reserve operator and none of them to be supplied to the normal operator. For this purpose a deflecting slide is provided which may be inserted into the receiving tube adjacent the lower part of the upper opening and at an angle to positively deflect all carriers through the upper opening or passageway.

Referring more particularly to the accompanying drawings, the carriers 10, are discharged downwardly through the lower end, 11, of a vertically positioned pneumatic dispatch tube and are received into a receiving tube, 12, positioned below, and forming a continuation of the discharge tube. The

lower portion, 14, of the receiving tube is slightly inclined or curved forwardly and has a correspondingly slightly inclined bottom or stop 16. The lower front portion of the receiving tube is provided with an opening or cut away portion, 18, through which the carrier 10 may be readily removed by the operator.

If carriers should be discharged through the tube, 11, at a rate greater than they can be accepted and disposed of by the operator, some of the carriers will be stopped in the upper portion of the receiving tube, 12, by unremoved carriers in the lower portion thereof. These carriers are therefore permitted to fall through, or are deflected through, an opening, 20, in the rear of the receiving tube above the lower opening, 18, and of a size sufficient to permit the carriers to drop therethrough. The inclined position of the carrier resting on the curved or inclined portion 14 of the receiving tube and the base or stop 16 may assist the deflection of the succeeding carriers through the opening 20.

At certain periods, there is ordinarily no overflow of carriers and no reserve operator is accordingly required. To avoid the passage of carriers to the position occupied by a reserve operator, in case two carriers should be discharged in close succession and both reach the receiving tube 12 before the former of them is removed, a guard or retainer is provided which may be moved into position to positively prevent the passage of carriers through the opening 20. This retainer or guard may be of any suitable form. A preferred embodiment shown in the accompanying drawing comprises a ring or collar 22 mounted on the discharge tube 11 and provided with a downwardly extending finger 24. The lower edge of the ring or collar 22 is supported on a collar 26 connecting the receiving tube 12 to the discharge tube 11 and is rotatable about the tube 11 with slight friction to permit the finger 24 to be moved directly back of the opening 20, to prevent the passage of carriers therethrough, or to a position at the side of the receiver to permit the ready discharge of carriers.

It is sometimes convenient to permit the operator to deflect all of the carriers discharged from the tube 11 to the reserve operator and leave the operator's desk free from the necessity of accepting and disposing of carriers. To this end a deflecting slide 28 is provided opposite the opening 20 in such a manner that it may be inserted into the receiving tube 12 to prevent the passage of carriers to the lower portion of the tube and to deflect them through the opening 20. The deflecting plate 28 is preferably formed of a triangular shape and has a sliding pivotal connection to the tube 12 by

means of which it may be lifted and swung through a slot 30 into and across the interior of the tube. The sliding pivotal connection is preferably formed by providing a slot or elongated opening 32 in the deflector plate 28 engaging a co-operating pin 34 mounted between ears or supports 36 projecting from the side of the tube 12. Any suitable connection, may, of course, be employed by which the deflector plate may be swung into and out of the receiver tube and held securely in either position. The deflector plate is held or retained in deflecting position in the receiver 12 by means of a notch 38 in the lower edge of the plate which engages an edge or projection 40 formed on the receiver tube by the lower end of the slot 30. The deflector is held out of the receiving tube by means of a notch 42 in the lower corner of the plate, which in the withdrawn position of the deflector, engages the projection or latch 40.

The operation of the invention is briefly as follows:

Carriers are normally discharged through the tube 11 to the lower part 14 of the receiving tube 12 from which they are removed by an operator having charge of the receiver. When an overflow or excess of carriers are discharged, these carriers are deflected by the presence of a carrier in the receiving portion 14 through an opening 20 and pass to a reserve operator. In case no reserve operator is provided and the normal supply of carriers is received at temporarily varying rates, the guard or retainer 24 is moved to position back of the opening 20 and all carriers discharged through the tube 11 are retained in the receiver until removed. To pass all the carriers any time to the reserve operator, the guard or retainer 24 is moved to the side of the receiving tube and the deflecting plate 28 is moved into the receiving tube to provide an inclined deflecting surface extending from the front wall 110 of the receiver 2 to the lower part of the opening 20. The carriers discharged pass directly to a reserve operator or may be delivered to a reserve operator by any suitable carrying or conveying means as shown.

It will be obvious that the invention may be embodied in other forms than that shown in the above specification and drawings and that the form of embodiment may be varied in adapting it to different conditions or circumstances without departing from the broader features of the invention.

Having described the invention, what is claimed as new, is:

1. The combination, with a pneumatic dispatch apparatus, of a tubular receiver having a lower carrier receiving portion and an opening thru which carriers may be removed therefrom and an opening above said receiving portion thru which carriers may

be discharged when said receiving portion is occupied.

2. The combination, with a discharge tube of a pneumatic dispatch apparatus, of a receiver having upper and lower openings, means for deflecting carriers through said upper opening at the will of the operator and a guard movable into position to prevent the passage of carriers through said

10 upper opening.

3. The combination, with a discharge tube of a pneumatic dispatch apparatus, of a receiver having upper and lower openings, a guard movable into and out of position to prevent passage of carriers through said upper opening, said guard being supported by means of a rotatably, sliding collar.

4. The combination, with the discharge tube of a pneumatic dispatch apparatus, of a receiver having upper and lower openings and a guard rotatable about said receiver to obstruct or free said upper opening.

5. The combination, with a carrier discharge tube of a pneumatic dispatch apparatus, of a receiver having upper and lower openings and a deflector plate arranged in one position to provide a deflecting guard

extending downwardly and rearwardly in said receiver at the lower portion of said upper opening to deflect carriers outwardly through said opening, said deflector plate being movable from said position to a position such that it no longer deflects carriers through the upper opening.

6. The combination, with a discharge tube of a pneumatic dispatch apparatus, of a receiver having upper and lower openings, a triangular plate having a sliding and pivotal connection to said receiver, notches at its lower edge, a co-operating slot in said receiver whereby one face of said plate may be held adjacent the forward face of said receiver or inclined downwardly toward the lower end of said upper opening.

7. A tube-shaped receiver for a pneumatic dispatch apparatus having a lower rear portion inclined forwardly and downwardly and the front portion adjacent thereto being cut away to permit the easy removal of a carrier and an opening in the rear of said receiver above said inclined and cut away portions to permit carriers to pass therethrough.

JAMES G. MACLAREN.
